FIG. 8

UNITED STATES PATENT OFFICE

EDWIN F. BRITTON, JR., OF MAPLEWOOD, NEW JERSEY, ASSIGNOR TO MONROE CALCULATING MACHINE COMPANY, OF ORANGE, NEW JERSEY, A CORPORATION OF DELAWARE

CALCULATING MACHINE

Application filed September 21, 1929. Serial No. 394,256.

The invention relates to means whereby a key-set calculating machine may be converted at will for simultaneous key responsive selecting and registering operation.

5 The invention consists in the novel construction and combination of parts, as set forth in the appended claims. In the accompanying drawings, illustrating the invention: Figure 1 is a side elevation, with parts broken away, of the key responsive mechanism of a calculating machine built in accordance with the invention.

10 Fig. 2 is a front elevation of the same, with the parts broken away.

15 Fig. 3 is a detail side view of the non-repeat key and associated parts.

20 Fig. 4 is a front elevation of the right-hand portion of the keyboard, with parts broken away, illustrating a modified form of the invention.

Fig. 5 is a detail front elevation of the non-repeat mechanism.

Fig. 6 is a plan view of the same.

25 Fig. 7 is a vertical section through the rear portion of the machine.

Fig. 8 is a detail left-hand elevation of the clutch operating mechanism.

30 These drawings illustrate the invention as applied to the Monroe calculating machine, disclosed in its essential features in Patent Number 1,566,650, granted to George C. Chase, December 22, 1925. The device of the present application attains certain results set forth in the co-pending application Serial Number 382,792, filed August 1, 1929, by Lee R. Brown, such results, however, being applied, according to the present disclosure, to a different use involving modified means.

35 According to the disclosure of Patent Number 1,566,650 above referred to, motor operation of the machine is controlled by movement of a rock shaft 125 (Figs. 1 and 2 of the appended drawings). Shaft 125 is rocked clockwise (Fig. 1) to engage a clutch (111, 110, 107) and set the machine for additive registration, and is rocked counter clockwise to engage the clutch and set the machine for subtractive registration, these movements of the shaft being controlled by suitable add and subtract keys. In this man-

55 ner, amounts set up on the keys 18, and thereby upon the column selector bails 19 and differential actuator gears 5, will be registered upon the numeral wheels, the depressed keys 18 being locked in active position by means of a bail 6.

56 In order to set the machine for key-controlled operation, a button 210 is pressed rearwardly, causing inclined lugs 208 on slide 209, to raise transverse frame members 211 upon which rest the slides 204 and thus lifting the teeth 203 of such slides into the path of movement of the keysystems 18. Depression of a key 18 will now cam the related slide 204 rearwardly, a pin 205 of the slide engaging lug 206 of a rocker arm 207 fast upon shaft 125, this movement causing clockwise rotation of said shaft and additive operation of the machine.

60 Operation of button 210 to set the machine for key-controlled operation, will also set suitable non-repeat mechanism into active position, this being accomplished by means of a cam lug 212 (Fig. 3) on slide 209, acting upon the pin 213 to rock a lever 214, fulcrumed at 215, in the direction of the arrow. The end of lever 214 engages a slot in the stem of non-repeat key 21, so that the non-repeat key will be locked in depressed position by pin 213 resting upon the top surface 65 of lug 212. The non-repeat mechanism set by key 21 is of well-known construction, illustrated for example, in United States Reissue Patent Number 16,207. According to this construction, the non-repeat key 21 is provided with a cam slot, adapted to set a lever 14 into the path of movement of a cam 16, fast on a driven shaft of the machine, said cam, through levers 14 and 15, moving a 70 slide 17 against the locking bails 6, to release the keys. Upon operation of the non-repeat mechanism to release the depressed key 18, the machine will complete the cycle of operation, whereupon the mechanism disclosed in Patent Number 1,566,650, will act

75 to stop the machine.

80 Means are provided whereby the machine may be set to operate subtractively under the control of the keys 18, this means comprising 85

90

95

100

Means are provided whereby the machine may be set to operate subtractively under the control of the keys 18, this means comprising 100

a button 200 having connection with a lever 201, fulcrumed at 202, and held in either of two adjusted positions by toggle spring 219, said lever having a pin engaging a slot 217 of the slide 204. When button 200 is in rearwardly adjusted position, the teeth 203 of slide 204 will present forwardly inclined cam surfaces to the stems of the keys 18. When, however, button 200 is drawn forwardly, slide 204 will be adjusted to bring the rearwardly inclined cam faces of the teeth 203 beneath the key stems, so that depression of a key 18 will now move slide 204 forwardly, bringing pin 205 in contact with the lug 221 of rock arm 207, to rock shaft 125 in a counter clockwise (or subtractive) direction as view in Figure 1.

The machine may be re-conditioned for key-set operation by drawing button 210 and slide 209 forwardly, removing the lugs 208 from beneath the frame members 211, thus permitting the frame to drop and lower teeth 203 out of the path of movement of the key stems 18.

25 I claim :

1. In a calculating machine having operating means including a member operable by a single manipulative movement to determine and initiate positive or negative registration; an item key, and devices manually settable to determine positive or negative registering operation or non-operation of said member by said key.

2. In a calculating machine having numeral wheels and a plurality of banks of item keys each settable to determine a value to be registered; adjustable means related to one of said banks for initiating action of the machine upon depression of any item key of said bank to register upon said wheels all values represented by the depressed keys, adjustable means for releasing the set keys after the determination of a single registration of the key values, and a device manually operable to adjust said initiating means and said releasing means simultaneously to operative position.

3. In a calculating machine having numeral wheels, a plurality of banks of item keys each settable to determine a value to be registered; means related to one of said banks for initiating action of the machine upon depression of any item key of said bank to register upon said wheels all values represented by the depressed keys, and means manually adjustable to set the last named means to operative or non-operative position.

4. In a calculating machine having numeral wheels and a plurality of banks of item keys each settable to determine a value to be registered; means related to one of said banks for initiating action of the machine upon depression of any item key of said bank to register upon said wheels all values represented by the depressed keys, and means manually adjustable to set the last named means to de-

termine positive or negative registration or to non-operative position.

Signed at Orange, in the county of Essex and State of New Jersey, this 16th day of September, A. D. 1929.

EDWIN F. BRITTON, JR.
